UNITED STATES PATENT OFFICE.

SAMUEL A. YOUNG, OF WASHINGTON, DISTRICT OF COLUMBIA.

CAR-COUPING.

SPECIFICATION forming part of Letters Patent No. 374,030, dated November 29, 1887.

Application filed September 9, 1887. Serial No. 249,251. (No model.)

To all whom it may concern:

Be it known that I, SAMUEL A. YOUNG, of Washington, in the District of Columbia, have invented a new and useful Improvement in 5 Car-Couplings, of which the following is a specification.

My invention is an improved car-coupling seeking to provide simple and novel constructions whereby to effect the automatic dropping of the pin on the entrance of the link, and also simple means for adjusting the outer end of the secured link, in order that it may 10 properly enter draw-heads of different heights.

The invention consists in certain novel 15 constructions and combinations of parts, as will be described and claimed.

In the drawings, Figure 1 is a vertical longitudinal section of my improved coupling, the pin being lowered to secure a link, and 20 such link being shown elevated in dotted lines by the link-adjuster. Fig. 2 is a perspective end view of the coupling, showing the link-adjuster lowered. Fig. 3 is a horizontal longitudinal section of the coupling, showing the 25 link-adjuster, and also illustrating the lever for operating such adjuster. Fig. 4 is a detail view of the adjuster. Fig. 5 is a detail view of a removable wrench-like handle for operating the link-adjuster; and Fig. 6 is a detail 30 view of the pin-seat, dotted lines being employed to indicate a handle by which such seat might be set forward, in order to dispense with the spring when so desired.

The draw-head A, except in the particulars 35 hereinafter mentioned, may be of ordinary construction, being provided with a flaring link-socket, a, and with pin-holes 1 and 2 through its top and bottom walls. In the upper face of the bottom wall of the draw-head 40 I form a mortise, B, in advance of the pin-opening 2, which mortise has rearwardly-extended side wings, b, which extend back alongside the pin-opening 2, as shown. In this mortise I fit the link-adjuster, or, as it may 45 be termed, the "lifting-hook," C, the upper side of which when it is lowered forms, practically, a continuation of the surface of the base-wall of the draw-head. At its forward end the link-adjuster has a transverse angular 50 opening, 3, formed through it for the insertion of an operating shaft or handle, D, by which such link-adjuster may be turned to elevate its

rear end and so adjust the angle of the link held in the draw-head.

In the construction shown in Fig. 5 the shaft 55 is an angular shaft or handle-bar fitted to the opening 3, and which may be inserted in and removed from the different link-adjusters of a train, being adapted in use to be carried by the train-men and used on any of my improved 60 couplings when occasion requires.

While the said construction shown in Fig. 5 may be used, it is preferred to employ the construction shown in Figs. 2 and 3, in which the shaft is extended through the lifting- 65 hook or link-adjuster so forming a connection therewith, and has a crank-arm, d, which is joined, by a rod, E, or other suitable connection, with a lever, F, which is pivoted between its ends and usually extends at its handle end in convenient reach from the side of the car. By this construction the link-adjuster may be operated from the side of the car, and where desired the lever may extend to 70 both sides of the car; or separate levers may 75 be provided leading to the opposite sides of the car, as may be regarded most convenient.

At its rear end the link-adjuster has arms c, which fit in the wings b of the socket B, and which arms engage the side portions of a link 80 and tilt the link to elevate its outer end to any desired degree. At the outer edges of the extremities of the arms c, I form upturned teats or ears 4, which steady the engagement of the adjuster C with the link.

The described construction for adjusting the angle of the link is simple and will be found to efficiently serve the desired purpose.

For the purpose of preventing the removal of the link-adjuster from the draw-head I provide it at its pivoted end and in one or both sides with circular groove 5, concentric with the center of motion of the link-adjuster, which groove or grooves 5 are entered by a pin or pins, 6, projected from or through the draw-head. In the under surface of the top wall of the draw-head I form a groove or recess, F, which extends rearwardly from the pin-opening 1. The pin-seat G fits at its upper side in said groove F, and is movable back and forth therein, its lower side resting on the base-wall of the draw-head. I construct this pin-seat with a forward extension, g, at its upper side, on which the pin rests in the set position

of the parts, and below which the entering link strikes the seat to move it back and release the pin H, which in such case falls through and secures the link. I form this 5 seat of two sections—an upper one, I, and a lower one, J—which are united together after their insertion in the draw-head. By forming them in sections the upper section can be first inserted in the draw-head and fitted up in the 10 groove F and the lower section, J, be then applied and secured to the section I.

In connecting the sections I J, I form them at their front ends with overlapping portions—that is to say, one of them has a portion which 15 laps in front of the other—and a screw, K, is passed through said overlapping portion into the other section, uniting them rigidly together.

It is preferred to further brace the sections 20 I and J together by forming a tapered dovetail rib, i, on the under side of section I and forming the upper side of the section J with a dovetail groove or socket, j, fitted to receive such rib, the front wall, j', of the groove in 25 such construction being the overlapping portion through which the fastening is carried. By preference the upper side of the pin-seat is grooved longitudinally, which formation gives a better seat for the pin, and also reduces 30 the friction-surface of the pin-support, as will be seen.

The pin-seat may be pressed normally forward by a spring, as shown in Fig. 1, or such spring might be omitted and the pin-seat 35 formed or provided with a lateral arm or handle portion, as indicated in dotted lines, Fig. 6, which handle may project through a slot in the side of the draw-head to facilitate the movement of the seat forward by hand; or the hand 40 may be inserted in the mouth of the draw-head to draw the seat forward.

In operation the teats or ears 4 serve to straighten the link in the draw-head. Thus, if the link be in the draw-head with its outer 45 end inclining off to one side or the other, the operation of the link-adjuster to elevate the link will, by means of the ears 4, draw the link into proper position.

It will be understood that one of my 50 proved couplings might be secured on a locomotive to receive the long draw-bar or link which extends forward over the pilot, and the link-adjuster might in such connection be operated by the engineer or fireman. In such 55 construction the ears 4 might be useful when the long draw-bar has a lateral swing, or the ears may be omitted when such bar is fitted snugly to the draw-head.

I provide openings 7 through the base-wall 60 of the draw-head leading from the mortise B for the exit of dust, dirt, and the grindings produced by the contact of the parts in operation.

It will be understood that while I prefer to 65 form the link-adjuster in one piece it might be formed in two sections, as indicated in dot-

ted lines, Fig. 4, in which case the mortise B in the base-wall of the draw-head might be formed of two wings separated by an intermediate wall, as will be readily understood 70 from Fig. 4.

By pivoting the link-adjuster at its forward end, so that its rear end will in practice be up-tilted to engage the link, I avoid all danger of breakage of the parts should the link enter the 75 draw-head when the adjuster is elevated, as such a condition of things would only result in the adjuster being lowered by the force of the entering link.

Another advantage of such arrangement is, 80 that thereby a given movement of the link may be accomplished by less movement of the adjuster than if the adjuster were pivoted at its rear end.

Having thus described my invention, what 85 I claim as new is—

1. In a car-coupling, the combination, with the draw-head having its base-wall formed with a mortise in its upper side, of a link-adjuster seated in said mortise and pivotally supported 90 at or near its front edge, substantially as set forth.

2. The combination, in a car-coupling, with the draw-head, of a link-adjuster pivotally supported at its front edge and having its rear 95 edge arranged and adapted to engage the link, substantially as set forth.

3. In a car-coupling, the combination of the draw-head, the link-adjuster pivotally supported therein, whereby it may be tilted to 100 adjust the angle of the link, and having a curved groove formed concentric with the center of motion of the link-adjuster, and a pin projected from the draw-head and entering the curved groove in the link-adjuster, substantially as and for the purposes specified. 105

4. In a car-coupling, a draw-head having a pin or projection, 6, combined with a link-adjuster consisting of a block or plate having at one end a transverse non-circular opening 110 and a curved groove, 5, and provided at its opposite end with arms e, having upturned teats or ears 4 at the outer edges of their extremities, substantially as and for the purposes specified. 115

5. The combination of the draw-head and the link-adjuster pivotally supported at one end and provided at its other end with teats or ears projected upwardly at its opposite sides, substantially as set forth. 120

6. In a car-coupling, the combination of the draw-head having one of its walls provided internally with a longitudinal groove and the pin-support bearing at one side within said groove and at its opposite side against the opposite wall of the draw-head, substantially as set forth. 125

7. The combination of the draw-head having a groove, F, the pin-seat section I, fitted at one edge in the groove F and having a rib, i, 130 on its opposite edge, and the section J, having a dovetail groove, j, fitted to receive rib i, and

- having its front wall, j' , overlapping said rib i , and a screw, K, passed through wall j' and entering the rib of the section I, substantially as set forth.
- 5 8. In a car-coupling, the combination of the draw-head and the pin seat or support formed of upper and lower sections, one of which has a portion overlapping the end of the other, and a connection for uniting such sections 10 passed through the said overlapping portion, substantially as set forth.
9. In combination with the draw-head, the pin seat or support formed of two sections, I and J, provided, respectively, with a dovetail rib and socket, substantially as and for the 15 purposes specified.
